UNITED STATES PATENT OFFICE.

JOHN W. KAUFMANN, OF BALTIMORE, MARYLAND.

REPRODUCER FOR TALKING-MACHINES.

1,347,813.

Specification of Letters Patent. Patented July 27, 1920.

Application filed May 10, 1919. Serial No. 296,088.

To all whom it may concern:

Be it known that I, JOHN W. KAUFMANN, a citizen of the United States, and a resident of Baltimore, in the State of Maryland, have invented certain new and useful Improvements in Reproducers for Talking-Machines, of which the following is a specification.

My invention is an improvement in reproducers for talking machines, and has for its object to provide a new and improved connection between the needle and the diaphragm controlling lever, which will eliminate the usual rigidity between these parts, substituting a resilient connection.

In the drawings:

Figure 1 is a perspective view of the improved reproducer;

Fig. 2 is a front view;

Fig. 3 is a vertical section;

Fig. 4 is a perspective view of the reproducer case;

Fig. 5 is a partial perspective view of a section of the inner gasket;

Figs. 6 and 7 are perspective views showing modified methods of clamping the springs to the case.

In the embodiment of the invention shown in Figs. 1 to 4, the case 1 of the reproducer box has the usual central nipple 2 for receiving the inlet end 3 of the amplifier, and it will be noticed, referring to Fig. 3, that the case has an inwardly extending annular rib 4 against which the end of the

amplifier abuts. The amplifier is held in the case by means of screws 5 having tapering points which engage tapering openings 6 in the amplifier, and it will be evident that when the screws are turned home the amplifier is drawn toward the rib to cause the same to fit tightly against the rib.

The diaphragm 7 is of usual construction, being held in place in the case by means of gaskets 8 and 9. This gasket 8, as shown in Fig. 5, is formed from rubber or the like, which is doubled at its center, the doubled sides diverging, as shown, away from the center of the washer, and a series of openings is provided at the apex of the bend, and at the point where it touches the diaphragm. At diametrically opposite points the case 1 has extensions 10, and with each extension is connected a pair of bearing pins 11.

These pins, as shown, are connected with the case and have rounded outer ends which engage within tapering openings 12 in holding bars 13. These holding bars have openings for receiving the ends of wicket or U-shaped springs 14, three springs being provided in the present instance. Thus the bars 13 are pivoted on the pins 11, and it will be noticed that the said pins have their axes approximately in the plane of the diaphragm. The bars are freely movable on the pins and are pressed toward the pins by the resiliency of the springs 14. With one of these bars is connected the lever 15 which is connected to the diaphragm at its center in the usual manner. The other bar 13 carries a needle holder 17 of usual construction, carrying the needle 18 held in place in the holder by the set screw 19.

The needle engages the record in the usual manner, and it will be evident that when the needle is moved by the waves of the record grooves this movement will be transmitted through the springs 14 to the other bar 13 and by way of the lever 15 to the diaphragm, vibrating the same in accordance with the contour of the grooves.

The bars 14 are preferably as shown in Fig. 2, each bar consisting of an inner and an outer section, the sections having registering grooves for receiving the springs, and the sections may be secured together in any suitable or desired manner. With this arrangement the springs may be quickly and easily removed or replaced, when desired, for any purpose, and each spring is firmly clasped by the bars.

In the embodiment of the invention shown in Fig. 6 the springs 20 are held in place on the bar 21 by a clamping plate 22 which is secured to the bars by screws 23 or the like. No grooves are provided in this arrangement, the springs being clasped directly between the clamping plate and the bar.

In the embodiment of the invention shown in Fig. 7 the springs 24 are received in openings through the bar 25, which is solid, and each spring is engaged by a set screw 26 threaded through the bar. The gasket 9 is held in place on the diaphragm by a ring 26 which is secured to the margin of the case.

With the usual reproducer there is a rigid connection between the needle and the dia-

phragm lever. In the present construction this connection is resilient, and a softer, less metallic reproduction is the result.

It will be understood that as many springs 5 may be used as may be desired, as, for instance, one or many, and they may be brazed or otherwise secured to the bars 13 if desired. The pivot pins 11 fit snugly into the 10 sockets 12, but these sockets are tapering so that sufficient motion is permitted.

Referring to Fig. 3, it will be noticed that the sound box is annularly grooved or countersunk to receive the gasket 8. This brings the diaphragm nearer to the face of the 15 sound box.

The connection of the springs with the bars 13 may be varied in accordance with conditions. They are shown as outside of the connection of the lever, but it is obvious 20 that they might be level with the lever or inside the same, if desired.

It will be evident from the description that the usual stylus bar which connects the needle with the diaphragm is replaced by a 25 two-part construction, one of which, 13, supports the needle and the other of which, 15-16, is connected to the diaphragm, and that the said parts are connected by the springs 14.

30 I claim:

1. In reproducers, the combination with the sound box and the diaphragm, and the reproducing lever connected with the diaphragm, of bars arranged at opposite sides 35 of the reproducer box and mounted to rock thereon, one of said bars being rigid with the reproducer lever and the other carrying the needle holder, and a connection between the said bars, said connection being resilient, and comprising substantially U- 40 shaped springs, each having one end connected with one bar and the other with the other bar.

2. In reproducers, the combination with 45 the sound box and the diaphragm, and the reproducing lever connected with the dia-

phragm, of bars arranged at opposite sides of the reproducer box and mounted to rock thereon, one of said bars being rigid with the reproducer lever and the other carrying 50 the needle holder, and a connection between the said bars, said connection being resilient.

3. In reproducers, the combination with the sound box and the diaphragm, and the reproducing lever connected with the diaphragm, of bars arranged at opposite sides of the reproducer box and mounted to rock thereon, one of said bars being rigid with the reproducer lever and the other carrying 55 the needle holder, and a connection between 60 the said bars.

4. In reproducers, the combination with the sound box, the diaphragm, the reproducing lever connected therewith and the needle holder, of a substantially U-shaped 65 spring connecting the needle holder with the reproducing lever.

5. In a reproducer, the combination with the sound box, of a radial extension at one side thereof, a reproducing lever connected 70 with the diaphragm at its inner end and pivotally mounted on the extension at its outer end, a needle support pivoted to the sound box opposite the pivotal connection of the lever, and a resilient connection between 75 the pivotal connection of the reproducer lever and the needle support, said connection comprising an arched spring secured at one end to the lever and at the other to the needle support. 80

6. In a reproducer, a sound box having extending radially therefrom an extension, an arched spring having one end pivotally connected with the extension and the other end pivoted to the opposite side of the 85 sound box, a reproducing lever rigidly connected with the first named end of the spring at one end of the lever and with the diaphragm at the other, and a needle support rigidly connected with the spring at the opposite end. 90

JOHN W. KAUFMANN.
